TEMPERATURE CONTROL CONTAINER

James L. Finch, Patchogue, and Lloyd L. Young,
Rocky Point, N. Y., assignors to Radio Cor-
poration of America, a corporation of Dela-
ware

Application August 15, 1935, Serial No. 36,342

6 Claims. (Cl. 219—19)

This invention relates to a new and novel method of enclosing a rectifier tube of the mercury vapor type within a container.

An object of this invention is to provide a suitable container for a rectifier tube whereby the temperature within the container is accurately controlled.

Another object of this invention is the novel arrangement within the container of a thermostat and a ring-like heating unit surrounding the lower portion of the rectifier tube to maintain a desired heating temperature within the container. Also, provision has been made for allowing the entrance of cooling air by automatically opening and closing the top of the container.

This invention is a further improvement over a similar device disclosed by George L. Usselman in his copending application filed June 29, 1935, Serial No. 29,021, wherein it was found necessary for the successful operation of rectifier tubes, particularly the mercury vapor type, to maintain the temperature so that it does not drop lower than 59° Fahrenheit, or rise higher than 120° Fahrenheit, particularly when such rectifier tubes are used in remotely located radio transmitting stations.

A feature of this invention is a compact arrangement surrounding the rectifier tube by a heating unit which has associated therewith a snap switch and a thermostat in the form of flexible metallic bellows, the thermostat being linked to the snap switch for controlling the heating unit, and also for opening the cover of the container when it is desired to lower the temperature within the container.

This invention will be more completely understood by referring to the accompanying drawing, in which

Fig. 1 is a cross-section of the container; and Fig. 2 is a detailed arrangement of the linkage system.

Referring now to Fig. 1, 1 indicates the container which is preferably made of a glass cylinder and surrounds the mercury rectifier tube 2 whose temperature is to be controlled. Near the lower end of the cylinder is placed a heating unit 3 which is in the form of a ring concentrically arranged just above the base 4 of the rectifier tube. Connection is made to the heating unit 3 by a terminal 5 which is connected to the next terminal current source 6. A second terminal 7 is located in the wall of the cylinder 1 just above the terminal 5 to which is fastened on the outside wall a micro-contact snap switch 8. Con-

nected to the snap switch 8 is a lead 10 which completes the series connection of the heating unit 3.

The anode connection 11 of the rectifier tube 2 is completed by a flexible lead 12 which is taken through the side wall of the container by a terminal stud 13. The lower portion of the casing 1 is provided with a metallic end member 14 which provides the support for the tube socket 15. Directly above the anode 11 is a thermostat 16 expanding disc bellows 16 which is a pancake-shaped affair made of thin corrugated brass and filled with a gas such as ethyl chloride which liquefies within the temperature range that the device is intended to operate. This thermostat 15 is mounted on the lid 21 of the container 1 and operates pivoted link member 18 to which is fastened a link 19 arranged to operate the snap switch 8. One end of member 19 stops movement after operating the lever of switch 8 at a pivot point 9 located on the end of the snap switch operating lever. The upper portion of the container is provided with a cover 21 which is swung on hinge 22 at a pivot point 23, the pivot 23 being supported from the outside of the casing 25 by a member 24.

A short pivot member 25 is secured to the cover 21 and arranged with the thermostat element 16 to cause the cover to rise to a position indicated by the dash-lines 26 to allow circulation of air through the cylinder in order that the tube will not become overheated should the temperature rise above the desired upper range of the temperature.

In the operation of this device, as shown by Fig. 2, heat is supplied by the heating unit 3 until the temperature rises sufficiently to cause the bellows 16 to expand due to evaporation of the liquefied gas. The expansion of the bellows causes member 18 to move and through the medium of member 19 operates the snap switch 8 opening the circuit of the heating unit. In case the heat generated by the tube 2 in its operation should increase the temperature within the cylinder to a higher value than is required or that which is desirable for successful operation of the tube, then member 19 continues to move further and acts to permit cooling air to enter the container by having the lower end of member 19 pivot at point 9, and when the thermostat bellows expands 50 still further, the linkage mechanism causes the lid to rise to a position indicated by the dash-lines 26. This allows circulation of air through the cylinder and thus prevents the rectifier tube from becoming overheated.

When the temperature drops below the desired temperature range, the bellows 16 collapses to its smallest dimension. Under these conditions the snap switch 8 is closed and heat is supplied by 5 means of the heating unit 3.

Although only one embodiment is shown, it is to be distinctly understood that this invention is not limited to this embodiment, but such limitations as are clearly imposed by the appended 10 claims.

Having thus described our invention, what we claim is:

1. A temperature controlled container for enclosing a rectifier tube comprising a container, a 15 cover for said container a thermostat in the form of flexible bellows within said container and secured to said cover, a heating unit surrounding said rectifier tube, a switch mounted on the outside of said container which is connected to said 20 heating unit, and means for regulating heat within said container by a linkage system connected to said switch and actuated by said thermostat to disconnect the heating current and to open said cover upon an increase of temperature within 25 said container.

2. A temperature controlled container for enclosing a rectifier tube comprising a container, a cover for said container, a thermostat in the form of flexible bellows within said container and secured to said cover, an electrical heating unit adjacent said rectifier tube and means for regulating heat within said container by a snap switch which is supported by being connected to the wall 30 of said container and actuated by a linkage system 35 connected to said thermostat to disconnect the heating current and to open said cover upon an increase of temperature within said container.

3. A temperature controlled container for enclosing a rectifier tube comprising a container 40 having a pivoted lid portion to provide the circulation of cooling air around said rectifier tube, a thermostat secured to said lid portion and located within said container, a link member adjacent said thermostat and pivoted at one end of said lid, a heating unit within said container to provide heating means therefor, a switch connected to said heating unit, said link member arranged to operate said switch by being actuated by the 45

thermostat upon a change of temperature within said container.

4. A temperature controlled container for enclosing a rectifier tube comprising a cylindrical container having a pivoted lid portion to provide the circulation of cooling air around said rectifier tube, a thermostat secured to said lid portion and located within said container, a link member adjacent said thermostat and pivoted at one end of said lid, a ring-like heating unit within said 10 container to provide heating means therefor, and a switch connected to said heating unit, said link member arranged to operate said switch by being actuated by the thermostat upon a change of 15 temperature within said container.

5. A temperature controlled container for enclosing a rectifier tube comprising a container having a pivoted lid portion to provide the circulation of cooling air around said rectifier tube, a thermostat secured to said lid portion and located within said container, a link member adjacent said thermostat and pivoted at one end of said lid, a heating unit within said container to provide heating means therefor, and a switch supported on the outside wall of said container and 20 electrically connected to said heating unit, said link member arranged to operate said switch by being actuated by the thermostat upon a change 25 of temperature within said container.

6. A temperature controlled container for enclosing a rectifier tube comprising a cylindrical glass container open at the lower end thereof, the upper end of said container being provided with a lid portion to provide the circulation of cooling air around said rectifier tube, a support base for said rectifier tube secured to the lower portion of said container, a thermostat secured to said lid portion and located within said container, a link member adjacent said thermostat and pivoted at one end of said lid, and a heating unit within said container to provide heating means therefor, and a switch operated by said heating unit, said link member arranged to operate said switch by being actuated by the thermostat upon a change of temperature within said 30 container.
